United States Patent Office.

SAMUEL FAWCETT AND HENRY R. CORKHILL, OF ROCHESTER, NEW YORK.

Design No. 3,840, dated February 8, 1870.

DESIGN FOR A BREAD-TOASTER.

The Schedule referred to in these Letters Patent and making part of the same.

We, SAMUEL FAWCETT and HENRY R. CORKHILL, of the city of Rochester, in the county of Monroe, and State of New York, have invented and produced a new and original Design for Bread-Toasters, &c., of which the following is a specification.

Our design consists in the form of the clamp or rests for holding the food, and the "twists" that are formed in the arms, each of the said clamp-arms being composed of a single piece of wire, that is bent into substantially the form represented, with both ends resting in the handle, as hereinafter set forth.

As represented in the accompanying drawing, the clamp-arms A A are each formed from a single piece of wire.

At the extremity of the arms A are formed the rests B B, for holding the food, the portions of wire composing them being bent or curved into the scroll-forms represented at a a a, in the drawing.

The portions c c of the wire, which form the outer rims or bearings of the rests, extend around, and are connected, by means of the "twist" formed in the neck, by twisting the wires together, as shown at g g.

Thence the wires extend, in a parallel direction, to the handle h, in which the ends are secured.

The wire may be bent, so as to form various patterns of the scroll-work, and give it a similar and ornamental appearance; and, in addition, a broad and uniform bearing is afforded on both sides of the bread or other article of food that is clamped between them, so as to hold it securely, and prevent the liability of the food being broken by any uneven pressure of the clamps.

The "twists" g g also connect those portions of the wire, forming the arms, together, and prevent them from drawing apart, or becoming separated from each other.

What we claim as new and original, is—

The design for bread-toasters, &c., herein described, substantially as set forth.

In testimony whereof, we hereunto sign our names in the presence of two subscribing witnesses.

SAMUEL FAWCETT.
HENRY R. CORKHILL.
